UNITED STATES PATENT OFFICE.

WALTER F. MILLER, OF BROOKLYN, NEW YORK.

RAILROAD-TRACK CONNECTION.

SPECIFICATION forming part of Letters Patent No. 734,345, dated July 21, 1903.

Application filed March 10, 1903. Serial No. 147,112. (No model.)

To all whom it may concern:

Be it known that I, WALTER F. MILLER, a citizen of the United States, and a resident of the city of New York, borough of Brooklyn, in the county of Kings and State of New York, have invented a new and Improved Rail-Joint, of which the following is a full, clear, and exact description.

The invention relates to the construction of railway-tracks; and its object is to provide a new and improved rail-joint arranged to allow of joining the rail ends without the use of bolts, separate fish-plates, and the like and to prevent sagging of the track-rails and spreading thereof.

The invention consists of novel features and parts and combinations of the same, as will be more fully described hereinafter and then pointed out in the claims.

20 A practical embodiment of the invention is represented in the accompanying drawings, forming a part of this specification, in which similar characters of reference indicate corresponding parts in both views.

25 Figure 1 is a perspective view of the improvement, and Fig. 2 is a transverse section of the same.

The rail-joint chair is made of a single piece of metal and consists of a base A, from the 30 sides of which rise integral angle-plates B B', forming with the base A a longitudinal recess of inverted-T shape for the reception of the base and web portions of the adjacent ends C C' of the rails to be joined. The bottom members of the angle-plates B B' are extended sidewise throughout their length to form spiking-flanges D D', the under sides of which lie in the same horizontal plane that contains the upper surface of the base A.

40 Now in using the device the rail-joint chair is preferably supported at its ends on spaced ties E E', provided at their top with alined cut-out portions or recesses E² for the reception of the base A, so that the under sides of 45 the flanges D D' rest on the upper surfaces of the ties adjacent to the cut-out portions thereof. Now in order to securely fasten the rail-joint chair in position on the ties spikes

50 are driven through openings in the spiking-flanges down into the ties, as plainly illustrated in the drawings. If desired, the spikes may be driven down into the ties along the outer edges of the spiking-flanges instead of through the openings therein, as shown and above mentioned. The ends C C' of the rails 55 to be joined are passed into the recess of the chair from opposite ends, so that the rail ends meet at or near the middle of the chair, as plainly indicated in the drawings. Now by the arrangement described the rails are supported by the chairs, and the latter are in turn secured to the ties, as described, so that the rails are not liable to sag, and owing to the base A of the chair being let in in the ties 60 it is evident that the chair and the rails there-in cannot move sidewise, thus preventing spreading of the rails. It will further be seen that by the arrangement described no bolts and nuts, separate fish-plates, nor like devices are necessary to connect the rails 65 with each other. Endwise displacement of the rails is prevented, as the rails abut one against the other in the chair.

Having thus described my invention, I claim as new and desire to secure by Letters 75 Patent—

1. The combination of a tie having a recess in its upper face with a rail-joint made of a single piece of metal, comprising a base fitting the recess in the tie and angle-plates rising integrally from the sides of the base to form with the latter a longitudinal inverted-T-shaped recess for the reception of the rail ends, the bottom of the T-shaped recess being flush with the top of the tie, as set forth. 80

2. A rail-joint chair made of a single piece of metal, comprising a base, and angle-plates rising integrally from the sides of the base, to form with the latter an inverted-T-shaped recess for the reception of the rail ends, the 85 horizontal members of the angle-plates being extended at their sides beyond the sides of the base and above the same, to form spiking-flanges, as set forth.

3. The combination of a tie having a recess 90 in its upper face, with a rail-joint chair made

of a single piece of metal, comprising a base fitting the recess in the tie, and angle-plates rising integrally from the sides of the base, to form with the latter a longitudinal invert-
5 ed-T-shaped recess for the reception of the rail ends, the horizontal members of the angle-plates being extended at their sides be-

yond the sides of the base and above the same, to form spiking-flanges resting on the top surface of the tie, as set forth.
